(57) CLAIM

The ornamental design for an electronic media gateway housing, as shown and described.

DESCRIPTION

FIG. 1 is a top perspective view of a first embodiment of an ornamental design for an electronic media gateway housing; FIG. 2 is a bottom perspective view of the first embodiment thereof;

FIG. 3 is a top view of the first embodiment thereof; FIG. 4 is a bottom view of the first embodiment thereof; FIG. 5 is a front view of the first embodiment thereof; FIG. 6 is a rear view of the first embodiment thereof; FIG. 7 is a right view of the first embodiment thereof; and FIG. 8 is a left view of the first embodiment thereof.

FIG. 9 is a top perspective view of a second embodiment of an ornamental design for an electronic media gateway housing;

FIG. 10 is a bottom perspective view of the second embodiment thereof;

FIG. 11 is a top view of the second embodiment thereof; FIG. 12 is a bottom view of the second embodiment thereof; FIG. 13 is a right view of the second embodiment thereof; FIG. 14 is a left view of the second embodiment thereof; FIG. 15 is a rear view of the second embodiment thereof; and,

FIG. 16 is a front view of the second embodiment thereof. The broken lines in the drawings illustrate portions of the electronic media gateway housing that form no part of the claimed design.
